ELECTRIC RAZOR WITH RECIPROCATING BLADE

Frederick J. Kent, Glen Rock, N. J., assignor, by
mesne assignments, to Servo-Tek Products Co.,
Paterson, N. J., a corporation of New Jersey

Application February 12, 1948, Serial No. 7,826

4 Claims. (Cl. 30—45)

1

This invention relates to electric safety razors of the type in which a razor blade is reciprocated in parallelism to its cutting edge.

Electric razors of this type are provided with razor blades which have to be held and guided accurately in order to avoid parasitic motions which would prevent a proper action of the device. The holding and guiding means however become easily clogged by the matter with which the razor comes into contact, and therefore reciprocation offers an increasing resistance, which when overcome leads to rapid wear of the guiding means with a consequent deterioration of the accuracy.

The invention has for its general object to provide holding means which exclude clogging and wear between the relatively moving elements.

A further object of the invention consists in providing holding and supporting means for the movable reciprocating blade carrying assembly which are fixedly attached to both the stationary and the reciprocating members.

A further object of the invention consists in providing resilient holding and supporting means for the reciprocating blade carrying assembly which are fixedly attached to the stationary and to the reciprocating member with surfaces substantially parallel to the direction of reciprocation and which are also holding the reciprocating members in engagement with the reciprocating impeller driven by the motor.

A further object of the invention consists in using a closed annular resilient support for guiding the reciprocating assembly and for holding it in engagement with the reciprocating impeller of a motor, which resilient annular means will completely close the space between the stationary members and the blade carrying member to which it is attached and will therefore form a complete and perfect seal behind the cutting edges preventing the penetration or introduction of any fluid, solid or gaseous matter into the space occupied by the electric motor.

Further more specific objects will be apparent from the following detailed specification.

One embodiment of the invention is illustrated in the accompanying drawing. It is to be understood however, that the embodiment shown is not the sole way of applying the principle of the invention. This embodiment is shown by way of example only for the purpose of explaining the invention and one of the preferred modes in which it is contemplated applying this principle. Modifications of the example shown are therefore not necessarily departures from the invention.

In the accompanying drawing:

Figure 1 is an elevational sectional view of the electric safety razor showing a longitudinal section along the plane of symmetry.

Figure 2 is an elevational sectional view of the electric razor shown in Figure 1, showing a trans-

2

verse section along a median plane of symmetry at right angle to the longitudinal plane of symmetry.

Figure 3 is an exploded isometric view of the razor.

Figure 4 is an elevational sectional view of a detail.

The electric razor, illustrated in Figures 1-3 is mounted on a handle 5 housing the electric driving motor for the blade which may be of any approved type and is not shown in the drawing. Any oscillating motor may be used, as the invention is not connected with the nature or type of the said motor. By way of example reference may be made for instance to my co-pending application Serial No. 9,180, filed February 18, 1948, which issued on August 1, 1950, as Patent 2,517,214, describing an improved type of oscillatory motor suitable for the driving of the razor blade.

For the purposes of the present invention, however, it is sufficient to state that every such oscillatory motor, whether producing the oscillatory movement directly or indirectly is provided with an impeller 6 which is connected with the reciprocating parts of the electric razor.

The handle 5 which is, as a rule, made of insulating material, such as plastics or the like, has a tubular extension 7 holding a tubular sleeve 8 projecting from the guard plate 9. The sleeve 8 fits snugly into the said extension and is cemented to it, so that the guard plate and the handle 5 form a unit.

The reciprocating members comprise the blade holder plate 10 which is provided with a central hole 11 and with blade holding projections 12 entering the slots 13 provided in the razor blade 15. This plate may have a curved central portion 13 if thin curved razor blades are to be held by it. This central portion is however surrounded by a flat edge portion 14.

On this carrier plate the blade 15 is secured by means of the retainer plate 16, which has a curved underside when used in connection with a curved razor blade. This plate again, is provided with a central hole 17 through which the threaded stud 20 may pass. The stud binds the carrier plate, the razor blade and the retainer plate together. It projects from the base of a cup like ferrule 25, to which it is firmly secured, and which turns its open side downwardly. Into this open side of the ferrule 25 the end 24 of the impeller 6 enters, thus imparting to the unit holding the blade the reciprocating motion, derived from the motor.

A knurled knob 23 with internal screw threads forming a nut serves to secure a firm grip of the blade holding members on the blade.

A rubber gasket 30 is vulcanized or cemented on both sides on the fixed and movable members respectively. On one side the said rubber gasket 30 is vulcanized or cemented to the flat upper side

of the guard plate 9. On the other side it is secured in like manner to the underside of the flat outer portion 14 of plate 10. The movable and stationary members 9, 10, 15 and 16 therefore form in fact a single unit, sealing the interior of the handle completely against penetration or introduction of solid, liquid or gaseous matter.

The rubber gasket must be of sufficient resiliency to permit a reciprocating relative movement of the stationary and movable parts to which it is attached. It may have any desired profile or cross section, the rectangular cross section shown being only an example. The direction of movement of the parts, as will be clear, is essentially parallel to the cutting edges of the blades, so that the latter are reciprocated substantially in themselves. The plane in which the movement of each member occurs is therefore parallel to the surface of the guard member or parallel to the planes passing through the two cemented surfaces of the gasket and these surfaces remain in the same plane during the reciprocating movement. The movement occurs at a rapid rate, connected, as a rule, with the number of cycles of the alternating current energizing the oscillatory electrical motor and does not exceed 0.010 inch. An amplitude of much less than this value would impair the slicing movement of the blade, but the amplitude, even if the resiliency of the rubber gasket is disregarded, cannot exceed this value to a large extent, as the blade would otherwise cut into and hurt the skin. A movement of this small extent may be safely taken up by the elasticity of the gasket. It will therefore be clear that the rubber gasket serves simultaneously as a support for the movable blade carrying assembly holding the latter in operative relation with respect to the guard plate and to the impeller of the motor, as a very accurate guide, holding the carrier plate, as well as the blade, in its own plane during the movement in which the active cutting parts are reciprocated along a line which coincides with said parts and as a perfect sealing means for the casing housing the electric motor.

On account of its movement in its own plane the razor blade may be honed by holding a stationary honing means against the edge of the blade while it is reciprocated.

It will be clear from the above that the method and means of holding the blade on the carrier plate, or the nature of the blade which may be single edged or double edged have no connection with the invention and do not limit the unchanged application of the invention in any way. Likewise, it will be clear that other unessential details may be changed without in any way affecting the invention.

Having described the invention, what is claimed as new is:

1. An electric razor of the reciprocating type comprising a handle, a stationary member on the same having a substantially planar surface, a reciprocating razor blade, a member carrying said blade coextensive with the stationary member, with edge portions substantially parallel to the said planar surface of the stationary member, a resilient member with two parallel surfaces, running along the said edge portions around the perimeter of the blade carrying member and joining the latter to the coextensive stationary member along its edge, one of the surfaces of said resilient member being fixedly adherent to the stationary member and the other surface being fixedly adherent to the reciprocating blade carry-

ing member for guiding the latter and the blade carried by it, when performing a reciprocating motion substantially in its own plane during reciprocation.

5. An electric razor of the reciprocating type comprising a handle, a stationary member provided with a substantially planar surface, a reciprocating razor blade, a member carrying said blade provided with a surface parallel to and facing said planar surface of the stationary member, means for reciprocating said blade carrying member, and a closed ring like resilient member fixedly attached to the two planar surfaces facing each other for guiding said reciprocating blade and carrying member and for producing a complete and permanent seal between said stationary and said reciprocating blade carrying member.

10. An electric razor of the reciprocating type, comprising a hollow handle, a stationary member fixed on said handle and provided with a substantially planar surface, a reciprocating razor blade, a member carrying said blade provided with a surface parallel to and facing said planar surface, a motor provided with a reciprocating impeller member projecting from said handle, said impeller member being loosely coupled with said razor blade carrying member for transmitting reciprocating motion, means for 15 supporting and guiding said blade carrying member during said reciprocating motion, said means consisting in a resilient annular member with two parallel faces, encircling completely the space between the surfaces of the stationary and the razor blade carrying member facing each other, the parallel faces of said annular member being attached to the surfaces of the two members facing each other respectively, said resilient member guiding and supporting the reciprocating blade carrying member along a plane substantially parallel to the direction of movement, and sealing the interior of the handle.

20. An electric razor of the reciprocating type comprising a hollow handle, a motor provided with an oscillatory member, and an impeller member, housed therein, a stationary guard plate fixed on said handle, provided with a planar surface, a razor blade, a blade carrying reciprocating assembly including a blade carrying member having a surface parallel to and facing the planar surface of the stationary member, a cup shaped member on said blade carrying member, enclosing the impeller member of the motor so as to be coupled for reciprocation only with said impeller, a resilient closed annular member with 25 two parallel surfaces, attached to the surfaces facing each other of the stationary and blade carrying member respectively, said annular member encircling completely the space between the stationary member and blade carrying assembly and forming a support and guide for the latter and a sealing means preventing penetration of matter into the hollow handle.
